UNITED STATES PATENT OFFICE.

FRED A. LUNDAHL, OF MOLINE, ILLINOIS.

LADDER AND ADJUSTING MECHANISM.

Application filed June 20, 1927. Serial No. 199,908.

While the present invention relates primarily to the construction of toys which are sufficiently durable to stand considerable usage and unusual wear, I desire it understood that certain features thereof are capable of use in similar articles for use other than as toys. The present invention relates to a new ladder construction and adjusting means whereby ladders may be adjusted in various directions.

Among the objects of my invention are to provide improved mechanism for the horizontal adjustment of ladders; to provide improved mechanism for the vertical adjustment of ladders; to provide an improved mechanism for the extension and shortening of ladders; to provide improved mechanism for the separation on the winding drum of the ladder extending and retracting cables; to provide an improved construction of ladder; and such further objects, advantages, and capabilities as will hereafter more fully appear and as are inherent in the mechanism disclosed. My invention further resides in the combination, construction and arrangement of parts illustrated in the accompanying drawings and, while I have disclosed therein a specific embodiment of my invention, I desire the same to be understood as illustrative only and not as limiting said invention.

In the drawings annexed hereto and forming a part hereof, Fig. 1 is an elevation of my invention mounted upon a suitable support, the latter being shown in outline by dotted lines; Fig. 2 is a broken plan view of the construction shown in Fig. 1, with the ladder extended; Fig. 3 is a longitudinal section of my construction detached from the truck and showing the ladder in elevated and extended position, sections of the ladder being broken out for the purpose of shortening the same; Fig. 4 is a cross section in front of the winding drum, looking rearward and showing the arrangement of the cables on the winding drum and the spacing means between said cables; Figs. 5 and 6 are similar views showing the positions of the parts when the ladder is fully extended and fully retracted; Fig. 7 is a cross section of winding drum just inside of one of the supporting arms therefor and showing means by which the ends of the cables are secured to the winding drum; Fig. 8 is a section through the flange of the supporting

member 9, looking upwardly, and showing the relative positions of the gears 5 and 8, pivots 6 and 10, and the meshing of the teeth 3 and 4; Fig. 9 is a cross section through the ladder, fully collapsed as shown in Fig. 1, said section showing more clearly the interfitting of the ladder sections shown in Figs. 1 and 3; Fig. 10 is a cross section substantially along the plane indicated by the line 10—10, Fig. 3; Fig. 11 is a fragmentary elevation of a portion of my device showing another type of lifting mechanism for the ladder; Fig. 12 is a similar view with the ladder shown in elevated position; Fig. 13 is a fragmentary transverse section substantially along the plane indicated by the line 13—13, Fig. 11.

Referring more in detail to the annexed drawing, numeral 1 designates a supporting body of any suitable type, herein shown as an automobile truck, while numeral 2 denotes a disc secured to the supporting body. Said disc 2 has gear teeth 3 rigidly secured thereto, the same being engaged by the cooperating teeth 4 on a pinion 5 carried by the rod 6 provided with a wheel 7. It will be understood, of course, that this mechanism may be varied as desired to produce the results intended. For example, the upper part of the disc 2 may be perforated at intervals to provide teeth taking the place of the teeth 3, herein shown as formed upon the edge of a disc 8 which is secured to the disc 2. In such a construction, the teeth 4 of the pinion 5 would be located enough lower than herein shown so that they would engage and cooperate with the teeth formed in the upper part of the disc 2. Various other constructions will suggest themselves from the foregoing and it is therefore not considered necessary to disclose these in detail.

A supporting member 9 is mounted upon the disc and pivoted thereon by means of a king pin 10 extending axially through the disc 2. This king pin is herein shown as being secured in place by means of nuts but any other suitable fastening means may be employed for this purpose.

Rising from the upper surface of the supporting means 9 are wings 11 to which is pivoted at 12 a ladder 13. The ladder has a bracket 14 secured to the lower end thereof, said bracket having upwardly extending arms 15 which are perforated for the re-

ception of the pivots 12. The bracket 14 comprises opposite side members connected by cross-bars 16 and is secured to the ladder in any desired manner, as by bolts 17.

5 Other supporting means rises from the upper surface of the supporting means or table 9, said other supporting means being designated by the numeral 18, in the present instance being shown as a pair of brackets. To these brackets are pivotally connected at 19 a pair of arms 20, the extremities of said arms being bent upwardly as shown at 21 to engage the sides of the ladder 13. A cross-bar 22 extends between the 10 arms 20 and is pivotally secured thereto, said arms being secured together by a plate 23 which has the edges thereof bent transversely to serve as stiffening means, the entire structure being reinforced in this manner, so far as practicable. The cross-bar 15 22 is perforated and screw-threaded for the reception of a correspondingly screw-threaded adjusting rod 24, the upper end of which passes through a cross-bar 25 which 20 is pivoted on the pivots 12. Longitudinal play of the shaft 24, with respect to the cross-bar 25 is prevented by the sleeves 26 and 27, the latter of which is secured to the shaft by the cross-pin 28. The shaft is 25 operated by means of a wheel 29, in the present instance shown as provided with a handle 30. It will be seen that as the shaft 24 is rotated by means of the wheel 29 it will move longitudinally through the cross-bar 30 22, thus causing relative motion between the shaft and the arms 20. Since the upper end of the shaft can not move longitudinally with respect to the wings 11 it results in the arms 20 moving and these, in turn, cause the 35 ladder 13 to move about its pivots 12. A stop 31 is provided so that when the ladder reaches a substantially vertical position the shaft 24 will engage said stop 31 and it will 40 be impossible to move the ladder any further.

45 It will be noted that the sections of the ladder are bent so as to have grooves 48 formed along one edge thereof and other grooves formed along the sides thereof so that the ladder sections will fit together and slide on each other freely but without undue looseness. The lower section 47, like the other sections, has its edge bent inwardly as indicated at 49 to form a groove along the 50 edge thereof. The arms 20 have their extremities bent outwardly as indicated at 20^a to slide in the groove 48 of section 47 and an edge of each arm 20 has formed thereon an angular projection 20^b to slide in the 55 groove formed by the flange 49. It will thus be seen that as the arms are raised by operation of the wheel 29 the end 20^a, sliding in the groove 48 elevates the section 47 to a more or less inclined position or even 60 a nearly vertical position. In turning the 65

wheel 29 in the opposite direction the arms 20 swing downwardly and the projections 20^b engage and slide along the flange 49 to pull the ladder downwardly toward a horizontal position, in event there is any resistance to such motion on the part of the ladder.

70 The winding drum 32 is mounted in perforations in the extremities 33 of the bracket 14, said extremities being offset laterally at 75 34 to get the ends of the winding drum beyond the sides of the ladder (see Fig. 2). In the present instance, the winding drum 32 is provided with fastening means 35 and 36 to which the ends of the cables 37 and 38 80 may be secured. These securing means 35 and 36 are located outside of the ladder, though this is not necessary. In the present instance it is desirable in order to make room on the winding drum.

85 In the present construction, the cable 38 extends from the winding drum 32 to a fastening means 39 at the outer extremity of the upper section 40 of the ladder. By this means, when the cable 38 is wound upon the 90 drum 32 the ladder sections will be pulled downwardly into collapsed position. Adjacent the near end of the section 40 of the ladder is a securing means 41 to which the extreme end of the cable 37 is secured. From here the cable passes over a pulley 42 at the outer end of section 45 and from thence under a pulley 43 and over the pulley 44. These pulleys 43 and 44 are carried by the near end of the intermediate section 100 45 of the ladder. From the pulley 44 the cable passes over the pulley 46 near the outer end of section 47 and down to the drum 32, this end being secured to one of the securing means 35, 36. From this it will 105 be apparent that when the cable 37 is wound upon the drum 32 it will be pulled over the pulley 46, thus moving the sections 45 and 40 upwardly to extend the ladder at its lower part. Due to the friction in the pulleys 42, 43 and 44 the upper section of the 110 ladder will not be extended until the lower part has reached its limit. This occurs when the stop 50 engages the stop 51. Motion of the upper section of the ladder is 115 limited by the stop 52 engaging stop 53. When collapsing the ladder the friction in pulley 46 is so much less than that in 42, 43 and 44 that the section 45 will come down to its lower limit before upper section 120 40 begins to travel. It will thus be seen that in extending the ladder the two upper sections will remain collapsed and will move together until the middle section has reached maximum extension and then the 125 upper section will move outwardly. In reverse action, the upper section will remain extended until the middle section has been lowered and then movement of the extreme outer section will take place.

It is believed that the operation of this device will be understood from the foregoing description but a brief statement will now be given. The rear end of the truck is provided laterally of the ladder with upwardly extending projections 55 which prevent the ladder from swinging sidewise until it has been elevated sufficiently to cause all parts thereof to clear all parts of the truck. 10 When the wheel 29 has been operated to raise the ladder to the desired inclination, the wheel 7 will be next operated to turn the table 9 and with it the ladder 13 to the desired direction. Having gotten the ladder in the desired direction the crank 56 connected with the winding drum 32 is operated to extend the ladder to the desired amount. This having been done, the latch 57 engages the notches in the ratchet wheel 58 to hold the ladder in extended position. 20 When it is desired to restore the ladder to its position upon the truck and operations are the reverse of those given above.

A spacing member, such as a washer 60, 25 separates cables 37 and 38 as shown in Fig. 4 and prevents them from coming in contact and interfering with each other during the winding operating. When the parts are in the position shown in Fig. 5 the ladder is 30 fully extended as shown in Fig. 2. As the crank 56 is turned counter-clockwise the cable 37 is unwound from and the cable 38 is wound on the drum 32, the spacer 60 being gradually moved along the drum until 35 the ladder is fully collapsed as shown in Fig. 1, the position of the winding parts being shown in Fig. 6. Fig. 4 shows the parts in an intermediate position.

In the construction shown on Sheet 3 of 40 the drawings a different type of lifting mechanism is provided for the ladders. In this construction an elongated supporting member 61, substantially U-shaped in cross section, is secured to the supporting member 45 9 in any suitable manner as, for example, by spot-welding. Within this supporting member 61 is a cylinder 62 which extends from near the forward end of supporting member 61 back nearly to the slots 63 in opposite 50 sides of the rearward prolongation of the supporting member 61, which is shown as being flattened on the top and bottom at 64. A piston mounted on the forward end of the piston rod 65 is slidable in the cylinder 62 and has a yoke 66 at its rearward end pivoted at 67 to the links 68. The ends of 55 the yoke 66 are slidable in the opposite slots 63, the yoke being forced rearwardly by means of a spring 69 located in the cylinder 62 and causing motion of the piston and piston rod in that direction. When the 60 ladder is free to move, the spring, through the piston, piston rod, yoke and links causes the ladder to be elevated to the position 65 shown in Fig. 12 or any desired intermediate

position between those shown in Figs. 11 and 12.

In order to transmit force from the spring to the ladder a yoke 70 having arms 71 bent downwardly at the ends thereof is secured to the under side of one of the cross bars 16. 70 The links 68 are pivotally connected at 72 with these arms of the bracket 70 and therefore transmit motion to the ladder. A sector 73 provided with notches 74 is rigidly secured to the arms 15 and therefore moves with the ladder as shown in Figs. 11 and 12. A bracket 75 is secured to the supporting member 9 and one of the wings 11 and has pivoted therein the end 76 of the lever 77. 75 A locking pawl or dog 78 is secured to the arm 76 of the lever and the forward end thereof engages any desired one of the notches 74 in order to stop and hold the ladder in any desired position of vertical 80 adjustment. A stop or stops 80, integral with the bracket 14, serve to limit the downward motion of the movable ladder sections.

From the foregoing it will be understood that the ladder 13 is manually lowered into 90 the position shown in Fig. 11 and the lever 77 turned from the position shown in Fig. 12 to that shown in Fig. 11 wherein the pawl 78 engages one of the notches 74 to hold the ladder in lowered position. The ladder will 95 then be maintained in this position until the lever 77 is turned forwardly to disengage the pawl 78 from the notches. When this is done, the spring 69 forces the piston backwardly in the cylinder 62 and causes 100 the links 68 to lift the ladder into an elevated position. If it is desired, the lever can be left in the forward position shown in Fig. 12 and the ladder will then rise to the vertical position as here shown. If it is desired to stop it at any intermediate position, 105 the lever is turned backward while the ladder is rising and engages one of the notches 74 to stop the ladder in such intermediate position. It will be understood that the 110 shaft 6 may pass thru the end of the cylinder 62 or not, as desired, but I prefer to secure the cylinder in place by passing the shaft through the end of it and thus avoid the necessity of using any other means to 115 fasten the cylinder in place.

The present application is a continuation in part of my prior application Serial No. 61,262, filed October 8, 1925 in which the examiner has held that the movability of the 120 spacer 60 was not disclosed in the application as filed. Since this is one of the important elements of my construction I consider it advisable to file this additional application clearly disclosing and claiming 125 that which was a part of my original invention and was invented before the filing of my prior application though the same was not stressed therein.

While I have disclosed herein preferred 130

embodiments of my construction, I desire the same to be understood as illustrative only and not as limiting said invention.

Having now described my invention, I claim:

1. In a truck, a sheet metal supporting body, a separate disc secured thereto, gear teeth rigid with said disc, an inverted cupped supporting member mounted upon said disc and carrying an operating member provided with a toothed member, the teeth of which engage with the aforesaid gear teeth, said supporting member being adapted to carry a ladder and to enclose the gears.
2. In a construction of the character indicated, a horizontally rotatable support, a cylinder secured thereon and having a piston therein, a spring to actuate said piston, a ladder pivoted on the support, a link connecting the ladder and piston, and pawl and ratchet means connecting the support and the ladder to hold the latter in various positions of vertical adjustment.
3. In a structure of the character described, a support, a partially tubular support mounted thereon, a cylinder within the last named support having a movable piston therein, a piston rod extending longitudinally of the cylinder beyond the end thereof, a ladder pivoted on the first named support, a part of the tubular support projecting beyond the cylinder having a slot therein, a yoke in said slot having connection with the piston rod, and a link connecting the yoke with the ladder.
4. In a structure of the character described, a support, a partly tubular support mounted thereon, a cylinder within the last named support having a movable piston therein, a piston rod extending longitudinally of the cylinder beyond the end thereof, a ladder pivoted on the first named support, a part of the tubular support projecting beyond the cylinder having a slot therein, a yoke in said slot having connection with the piston rod, a link connecting the yoke with the ladder, and means comprising a latch and sector connected respectively with the first named support and the ladder whereby the latter may be stopped and held in any desired position of vertical adjustment.
5. In a ladder, a support, a ladder section pivoted upon said support to turn in a substantially vertical direction, said ladder section being grooved along its under and inner faces for the reception of an actuating means, an actuating arm having a lateral projection to engage a groove in the inner face of the ladder section and having its

end engaging the groove in the under face 60 thereof to swing the same about its pivot.

6. An extensible ladder comprising a plurality of similar sections slidably connected with each other, each section being formed from sheet metal cut and pressed to form 65 a pair of side rails and a plurality of rungs, integrally formed, the side rails having substantially parallel longitudinal ridges so that the rails, in cross section, comprise a series of alternating ridges and grooves, the 70 ridges of one section interfitting with the grooves of the next.

7. In a ladder, a support, a ladder section pivoted upon said support to turn in a substantially vertical direction, said section being grooved for the reception of actuating means, actuating arms having lateral projections to engage grooves in the ladder section to swing same about its pivot, other similar sections slidably connected with each 80 other and with the first named section, each section being formed from sheet metal cut and pressed to form side rails and rungs connecting them, the rails and rungs being integrally connected, the side rails having 85 substantially parallel longitudinal ridges so that the rails in cross section comprise a series of alternating ridges and grooves, the ridges of one section interfitting with the grooves of the next.

8. In a structure of the character indicated, a support, an extensible ladder pivoted thereon, a notched sector connected to and traveling with the ladder about its pivotal point, a locking dog cooperating 95 with said sector to stop the ladder and hold it in relatively fixed relation with respect to the support, resilient means connected with the support for raising the ladder, and connections between the resilient means and the ladder for raising the latter from a lowered to an elevated position.

9. In an extension ladder, a supporting member, a ladder section pivotally mounted upon the supporting member, the side rails 105 of said section having depending flanges and being longitudinally grooved, a pair of lifting arms pivoted adjacent one end for actuation of the ladder about its pivot, each of said arms having a lateral projection to 110 engage a groove of each of said side rails of said ladder so that when the arms are actuated about their pivots they may transmit force to the ladder to turn it about its pivot.

In witness whereof, I hereunto subscribe my name to this specification.

FRED A. LUNDAHL.
